UNITED STATES PATENT OFFICE

EDWARD D. PUTT, OF AKRON, OHIO, ASSIGNOR TO THE FIRESTONE TIRE AND RUBBER COMPANY, OF AKRON, OHIO, A CORPORATION OF OHIO

MACHINE FOR GRINDING OR BUFFING ANNUAL ARTICLES

Application filed August 8, 1927. Serial No. 211,343.

This invention relates to grinding or buffing machines and has particular reference to semi-automatic machines for grinding, buffing or polishing annular articles.

5 The object of the invention is to devise means for grinding or buffing annular articles with accuracy, speed, uniformity and safety. A further object of the invention is to provide a machine comprising means for 10 grinding or buffing the inner periphery of an annular article, means for grinding or buffing its outer periphery, and means for engaging the sides thereof to rotate the article, all of said means being simultaneously movable toward said article. Another object is to provide a machine having a plurality of devices for grinding or buffing various parts of the surface of an annular article and means for rotating said 15 article past said devices.

The foregoing and other objects are obtained by the machine illustrated in the accompanying drawings and described below. It is to be understood that the invention is 20 not limited to the specific form thereof disclosed herein.

Of the accompanying drawings,

Figure 1 is a plan view of a machine embodying the principles of the invention; 25 Figure 2 is a rear elevation thereof; Figure 3 is a right end elevation thereof; Figure 4 is a vertical section taken on the line 4-4 of Figure 1; and

Figure 5 is a plan detail of a portion of the machine.

Referring in particular to the drawings, 10 represents a lower base plate from which extend four standards or legs 11 for supporting an upper work table 12. Hinged arms 13 and 14 are provided on one end of each thereof with sleeves 15 and 16, respectively, journaled between plate 10 and table 12, while the free ends of the arms are provided with sleeves 17 and 18, respectively, in which are journaled shafts 19 and 20. The upper ends of sleeves 17 and 18 pass through a slot 21 in the table 12, permitting motion of the sleeves toward and from each other, as illustrated in Figure 5. Abrasive, polishing or buffing wheels

or rasps 22 and 23 are fixed to the upper ends of shafts 19 and 20, and the lower ends of the latter are provided with pulleys 24 and 25 adapted to be driven by belt 26 which is trained thereover and around drive pulley 27 and idler pulley 28. Drive pulley 27 is fixed on the shaft 29 of a motor or other power source (not shown) supported beneath the base plate 10. A rock shaft 31 journaled in hanger 32 has fixed at its inner end a double lever arm 33 and at its outer end a double lever arm 34. Links 35 and 36 have universal hinge connections with studs 37 and 38, respectively, mounted in arms 13 and 14 and are, in turn, connected to the opposite ends of lever arm 33, as best shown in Figure 4. A tension spring 39 attached to one end of lever 34 normally maintains shaft 31 and lever arm 33 in a position to spread arms 13 and 14 apart, while attached to the other side of lever arm 34 is a connecting rod 40 operated by a suitable pedal (not shown) to rock said shaft and turn lever arm 33 with its connecting links to draw arms 13 and 14 toward each other.

In order to rotate annular articles 41, indicated by dotted lines in Figure 1, circumferentially past the grinding or buffing wheels, a friction-drive roller 42 is provided. This roller is fixed to a shaft 43 journaled in the free end of an arm 44 hinged with respect to table 12, the roller being driven from motor shaft 29, the driving means consisting, in turn, of pulley 45, belt 46, pulley 47, pinion 48, gear 49, bevel gears 50 and 51, sprocket 52, chain 53 and sprocket 54, arranged as illustrated. A lever 55, pivoted to table 12, is provided with a lug 55^a engageable with arms 44 and is operable by lever arm 34 through connecting rod 56 for lowering friction drive roller 42 upon the article 41 simultaneously as the grinding or buffing wheels 22 and 23 come together. A weight 57 is slidable along a bar 58 attached to arm 44, in order to regulate the downward force of roller 42 upon the article. The latter is vertically supported by a roller 59 directly beneath drive roller 42, and by rollers 60 mounted in table 100

12 and projecting slightly above the surface thereof, while adjustably mounted guide rollers 61 engage the periphery of the annular article to maintain the same in a correctly centered position and permit various sizes of articles to be accurately guided between wheels 22 and 23.

In operation, an annular article to be ground or buffed is placed between the guide rolls, rotating wheels 22 and 23 being apart and driven roller 42 being raised as shown in Figures 1 and 2. The pedal is then pressed down, which action simultaneously draws wheel 22 against the inner periphery 15 of the article, wheel 23 against the outer periphery and roller 42 against the upper side face thereof as illustrated in Figure 4. After article 41 is completely circumferentially rotated or passed between wheels 20 22 and 23 sufficiently to complete the operation, the pedal is released and the article removed. The article will be found to be accurately ground or buffed, and a number of such articles may be rapidly and uniformly finished upon the machine with a minimum of manual labor and with safety for the operator.

Modifications of the construction herein disclosed may be resorted to without departing from the spirit of the invention or the scope thereof as defined by the appended claims.

What is claimed is:—

1. A machine for grinding or buffing annular articles, said machine comprising a pair of rotatable abrasive wheels, means for pivotally mounting said wheels for motion toward and from each other, means for normally holding said wheels apart including a pair of links connected respectively to each of said mounting means, a lever arm having its ends connected to said links and adapted to be partially rotated for drawing said wheels together, and a rotatable friction drive roller, said roller being hingedly mounted with respect to said wheels and adapted to be lowered toward the latter to engage one of the articles for rotating the same circumferentially past said wheels.

2. A machine for grinding or buffing annular articles, said machine comprising a pair of rotatable abrasive wheels, means for pivotally mounting said wheels for motion toward and from each other, means for normally holding said wheels apart, a rotatable friction drive roller, said roller being hingedly mounted with respect to said wheels and adapted to be lowered toward the latter to engage one of the articles for rotating the same circumferentially past said wheels, and means for simultaneously drawing said wheels and said roller together about said article.

3. A machine for grinding or buffing annular articles, said machine comprising a

pair of rotatable abrasive wheels, means for pivotally mounting said wheels for motion toward and from each other, means for normally holding said wheels apart, a rotatable friction drive roller, said roller being adapted to engage one of the articles for rotating the same circumferentially past said wheels, and means for simultaneously drawing said wheels and said roller together about said article.

4. A machine for grinding or buffing annular articles, said machine comprising a pair of rotatable abrasive wheels, means for pivotally mounting said wheels for motion toward and from each other, means for normally holding said wheels apart, means for drawing said wheels together, and a rotatable friction drive roller, said roller being hingedly mounted with respect to said wheels and adapted to be lowered toward the latter to engage one of the articles for rotating the same circumferentially past said wheels.
